GEORGE LEFEVRE, OF LAWRENCE, MASSACHUSETTS.

SHADE-ROLLER SUPPORT.

1,142,589.

Specification of Letters Patent.

Patented June 8, 1915.

Application filed August 17, 1914. Serial No. 857,151.

To all whom it may concern:

Be it known that I, GEORGE LEFEVRE, a citizen of Canada, residing at Lawrence, in the county of Essex and State of Massachusetts, have invented certain new and useful Improvements in Shade-Roller Supports, of which the following is a specification.

My invention relates to supports for window shades of a type which can be attached to the window casing without screws or nails. It is of such construction that it can be attached to the casings of windows of the widest or narrowest types generally in use. It is also of such character that it can be so attached as to receive rollers which are extra long or extra short as it has a wide range of adjustment.

In the drawings Figure 1 is an elevation from the inside of a room showing my supports in place with a window shade supported thereby the supports being in what may be called their normal positions. Fig. 2 is an elevation similar to Fig. 1 showing my supports attached and adjusted for an extra long window roller. Fig. 3 is a front elevation of one of my supports and Fig. 4 is a side elevation as from the right of Fig. 3. Fig. 5 is a bottom view of Fig. 3 some parts being omitted. Fig. 6 is a detail showing the bracket for that end of the shade roller which is usually provided with a cylindrical bearing pin.

A and B represent the two sides of a window casing and C and D are window shades of different widths.

F and G are my two supports which are similar except that one is arranged to ordinarily be used on the right and the other on the left of the window casing.

Referring to support F, it comprises an outer member 10 which I will call the fixed member which is bent at a right angle to form a jaw 11 and is provided at the inside thereof with spurs 12 and which is bent down at the sides 13 to receive slidably the inside member or slideable member 20. This slideable member 20 is bent at a right angle to form a jaw 21 on the inside of which are spurs 22.

To the outside of inside member 20 is fixed a bearing pin 23 which projects through a longitudinal slot 14 in outside member 10. Pivotedly attached to pin 23 is one end of a link 15 the other end of which is pivotally connected at 16 with a handle 17. This handle 17 consists preferably of a flat piece

of metal from each end of which are bent upwardly finger pieces 19 and 18 at such distances that 19 can be gripped between the thumb and index finger while 18 can be gripped between the base of the thumb and the second finger. This construction permits handle 17 to be firmly grasped and pulled outward when desired. Handle 17 is pivotally carried by a headed pivot pin 30 fixed to outer member 10. It projects through 17 and is encircled by a compression spring 31 held between its head and handle 17 whereby handle 17 is normally pressed against outer member 10.

When it is desired to bring the jaws 11 and 21 together in order to clamp the device in place on the sides A or B of the window casing, it is necessary only to move handle 17 about its pivot whereby link 15 through pivot pin 23 causes inside member 20 to move back from or toward jaw 11.

To lock the parts in place when the jaws have grasped the side A or B I prefer to cut a plurality of notches 32 into the face of outer member 10 in a curve the center of which is the center of pin 30. To engage these notches 32, I cut from the end part of handle 17 preferably in the lower part of finger piece 18, a tang 34 and press it inward in such a manner that it will engage the notches 32 while handle 17 is pressed inward by spring 31. To disengage tang 34 from any of the notches 32, finger pieces 19 and 18 are grasped by the hand as described and the whole of handle 17 is pulled outward and turned while in the outward position. This clamping part of my support can be clamped to either side of the window frame and either side up.

Preferably integral with outer member 10 is a lateral extension 40 which preferably is of a length somewhat greater than half the length of outer member 10 and of a length somewhat more than half as great as the extreme width of the widest window frame or casing to which it is to be attached.

At each end of lateral extension 40 are bent outwardly the arms 41 and 42. Each of these arms is pierced with preferably three holes such as 43, 44 and 45 to receive the connected bearing rods 50, 51, 52. At one end this set of rods 50, 51, 52 are connected as shown at 53 in Fig. 3. They are equal distances apart as are the holes through which they pass in arms 41 and 42.

so that they can be pushed in from the outside of other arm. One of them as 51 is pierced by a hole 54 through the free end and through this is passed a split ring 55 5 which can readily be removed.

Slidably on bearing rods 50, 51 and 52 which pass through suitable bearing holes therein is a shade bracket 60 which extends outward beyond the arms 41 and 42 a sufficient distance to permit the roller of the shade C or D to clear such arms. One of these brackets as 60 has a rectangular opening 61 to receive the rectangular pivot pin ordinarily used at one end of a shade roller. 10 The bracket 62 which is slidable on support G has a round opening 63 to receive the cylindrical bearing pin ordinarily used at the other end of a window shade roller.

I prefer to split bracket 60 at the bottom 20 into two branches 64 and 65 through both of which pass suitable bearing holes through which pass bearing rods 50, 51 and 52. By thus forming two branches the bracket will slide more readily without binding upon 25 the bearing rods.

Encircling one of the bearing rods, preferably 51, which carries the split ring is compression spring 56 which extends between bracket 60 and one of the arms as 41. 30 The construction of the other support G in reference to its clamping mechanism and also in reference to its spring bracket mechanism is the same as F except that its lateral extension 48 extends upwardly from the left 35 while from F it extends upwardly from the right.

The bearing rods of both should be of the same size and spaced about the same distance as should the holes through which they 40 pass in the brackets 60 and 62 and in the arms 41 and 42 and the corresponding arms 67 and 68 of support G.

The method of clamping my device in place has already been described and when 45 in position and locked by means of locking tang 34 and notches 32, the shade as C is put in place by inserting its bearing pins respectively in openings 63 and 61 which can readily be done by forcing the brackets 60 and 62 away from each other against the tension of their respective springs.

With the supports F and G in their normal positions as shown in Fig. 1, it will be seen that shades of different lengths corresponding with the limits of compression and extension of the respective bracket springs as 56 may be used but my device has a greater range of adaptability as will be now explained.

60 If it is desired to support a shade such as D which is so wide that it cannot be held by my supports in their normal positions I attach support F to side B instead of to side A and I attach support G to side A instead of 65 to side B. This brings the brackets 60 and

62 on the outside instead of on the inside where they must be to properly engage the bearing pins of the window shades and in order to place them in their proper position I move the split rings as 55 which permits 70 the bearing rods of each support to be removed and to be passed through the arms as 41 and 42 from the opposite direction as shown in Fig. 2 and to exchange the brackets 60 and 62 so that the rectangular hole 61 75 will come at the proper end of the shade as will also the round hole 63. In this way, as the lateral extensions which carry the spring actuated shade brackets are more than half as long as the outside members, when the 80 sides are reversed the range is almost double and a shade of any width between the extremes can be readily supported.

With my construction the curtain shade supports can be attached or detached to any 85 window casing or to the top corner blocks without marring the face thereof. The only marks are those of the spurs on the edges of the casing and these are very inconspicuous. My supports are intended to go 90 with a shade so as to permit it to be attached to substantially any window casing of a size within the usual limits. It is detachably attachable and the parts of each pair are interchangeable. Substantially the only difference 95 between the parts of each pair is that the lateral extension is from the left of one and from the right of the other, while one bracket has a rectangular opening for rectangular bearing pin 70 and the other has a 100 round opening for cylindrical bearing pin 71 of the shade roller.

In order that there may be no length of window shade roller between the limits of the device to which it cannot be fitted, the 105 distance between the outwardly bent arms and the lateral extension should be more than one half of the maximum distance between the clamping jaws.

I prefer to use in connection with each of 110 my supports, a curtain pole holder 80 which consists of a rod bent to form a bracket. To receive this holder 80, I expand a loop 81 from the metal of each lateral extension of a size to receive the end of a holder. 115 Each holder preferably has a slot 82 which fits over the edge of a loop thus holding it at its proper height and preventing it from turning.

I find it convenient to connect one end of 120 the bearing rods as at 53 so that they can be removed and replaced together.

As my rectangular holed and round holed brackets are interchangeable, my supports can be used at the top or bottom of the window casing.

I am aware that spring actuated shade roller brackets have been used and I am aware that roller brackets which can be clamped to the window casings have been 130

used, but I believe that I am the first to combine a pair of spring actuated brackets with clamping devices for attaching them to the window casings, whereby my supports can instantly be put in place or removed without marring the face of the window casing, and upon which the shade roller can be instantly hung. Moreover, I am the first to devise a combination of clamping device and reversible, interchangeable, spring actuated roller brackets whose limits of action extend substantially the distance between the jaws of the clamping device.

The purpose of my invention is to provide shade roller supports which can adapt themselves instantly to support a shade roller of any ordinary length on a casing of any ordinary width which borders a window of any ordinary width.

Instead of three bearing rods with suitable bearing holes, I may use any other number more than one, that is a plurality.

I claim:—

1. The combination with a window shade roller having at one end a rectangular bearing pin and at the other end a cylindrical bearing pin, of a pair of supports each of which is provided with clamping jaws for detachably attaching it to either side of a window casing, and each of which has a lateral extension with outwardly bent arms the distance between which is more than one half the maximum distance between the clamping jaws and each of which is pierced with three holes, a set of three connected bearing rods which extend through said holes in each support, a split ring removably attached to one of the bearing rods of each set, and a compression spring which encircles one of the rods of each set between the arms, together with shade roller brackets interchangeably slidable on the bearing rods of either support and in engagement with the compression spring thereon, one having a rectangular opening to receive the rectangular pivot pin and the other having a round opening to receive the cylindrical pivot pin of the shade roller.

2. A window shade roller support which has clamping jaws and means for operating said jaws in such manner that the support may be detachably attached to a window casing, and a lateral extension with outwardly bent arms the distance between which is more than one half the maximum distance between the clamping jaws and each of which is pierced with three holes, three connected bearing rods which extend through said holes, a split ring removably attached to one of the bearing rods, and a compression spring which encircles one of the rods between the arms, together with a shade roller bracket slidable on the bearing rods and in engagement with the compression spring thereon.

3. The combination in a window shade roller support of means for detachably attaching it to a window casing, with outwardly bent arms each of which is pierced with a plurality of holes, connected bearing rods which extend through said holes, and a shade roller bracket slidable on the bearing rods, together with a compression spring between the bracket and an arm as described.

4. In a window shade roller support the combination of a spring actuated shade roller bracket, with means for detachably clamping said support to a window casing.

5. The combination in a window shade roller support of an outside member having a clamping jaw, an inside member slideable in the outside member and having a clamping jaw, with a headed pivot pin fixed to the outside member, a compression spring thereon, a handle pivoted to said pin and in engagement with said spring, a link pivotally connected with said handle and with the inside member, notches in the outside member and a tang depending from the handle in engagement with said notches, together with a lateral extension of the outside member which has outwardly bent arms the distance between which is more than half the maximum distance between the clamping jaws and each of which is pierced with a plurality of holes, a plurality of connected bearing rods which extend through said holes, a split ring removably attached to one of the bearing rods, a shade roller bracket slidable on the bearing rods, and a compression spring between said brackets and an arm as described.

6. In a window shade roller support the combination of a member which has outwardly bent arms each of which is pierced with a plurality of holes, with connected bearing rods which extend through said holes, a shade roller bracket slidable on the bearing rods, and a compression spring between the shade roller bracket and one of the arms as described.

7. The combination with a window shade roller having at one end a rectangular bearing pin and at the other end a cylindrical bearing pin, of a pair of supports each of which is provided with clamping jaws for detachably attaching it to either side of a window casing, and each of which has at the opposite end from the other a lateral extension with two outwardly bent arms the distance between which is more than one-half the maximum distance between the clamping jaws all of said arms being pierced with a plurality of holes of the same size and those in each arm having the same relative location, two sets of connected bearing rods each set adapted to pass through the holes in the arms of either support either way, and a compression spring which encircles

one of the rods of each set between the arms, a tangential opening to receive the rectangular together with two shade roller brackets in a pivot pin and the other having a round 20 interchangeableably slideable on the bearing rods opening to receive the cylindrical pivot pin of either support one in engagement with one of the shade roller each slideable in a support 5 each compression spring thereon and one support, together with spring mechanism in having a rectangular opening to receive the each support which tends to keep said rectangular pivot pin and the other having brackets in engagement with the window a round opening to receive the cylindrical shade roller.

In testimony whereof I hereto affix my 25 signature in presence of two witnesses.

10. The combination with a window shade

his
GEORGE X LEFEVRE.
mark.

roller having at one end a rectangular pivot pin and at the other end a cylindrical pivot pin, of a pair of supports each of which is capable of being clamped to either side of a window casing, with a pair of interchangeable shade roller brackets one having a rec-
